DESIGN FOR A COMBINED COLOR DIAL AND DISPLAY STAND

Mary Gorelick, New York, N. Y.

Application October 4, 1937, Serial No. 71,947

Term of patent 3½ years

To all whom it may concern:

Be it known that I, Mary Gorelick, a citizen of the United States of America, residing in New York city, in the Borough of Manhattan, county and State of New York, have invented a new, original, and ornamental Design for a Combined Color Dial and Display Stand, of which the following is a specification, reference being had to the accompanying drawing, forming part thereof, wherein,

Figure 1 is a plan view of a combined color dial and display stand showing my new design.

Figure 2 is a side elevational view of the combined color dial and display stand, and illustrating the drawer thereof.

The ornamentation shown on the front of the design is repeated around the other parts, which cannot be seen.

I claim:

The ornamental design for a combined color dial and display stand, substantially as shown, and described.

MARY GORELICK.
